(57) **CLAIM**

The ornamental design for a chair, as shown and described.

DESCRIPTION

FIG. 1 is a front, right and top perspective view of a chair showing my new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a front, right and top perspective view of a chair, shown in a first alternate configuration;

FIG. 9 is a front, right and top perspective view of a chair, shown in a second alternate configuration;

FIG. 10 is a front, right and top perspective view of a chair, shown in a third alternate configuration; and,

FIG. 11 is a rear, right and bottom perspective view thereof, shown in the third alternate configuration.

The thin broken lines depict portions of the chair that form no part of the claimed design.

1 Claim, 11 Drawing Sheets
